FIG. 3.

UNITED STATES PATENT OFFICE.

JOHN M. HOPWOOD, OF DORMONT, PENNSYLVANIA.

REGULATION AND APPARATUS THEREFOR.

1,338,928.

Specification of Letters Patent.

Patented May 4, 1920.

Application filed April 21, 1919. Serial No. 291,780.

To all whom it may concern:

Be it known that I, JOHN M. HOPWOOD, residing at Dormont, in the county of Allegheny and State of Pennsylvania, a citizen 5 of the United States, have invented or discovered certain new and useful Improvements in Regulation and Apparatus Therefor, of which improvements the following is a specification.

- 10 The invention described herein relates to the regulation of combustion conditions such as supply of fuel and air for the proper combustion of fuel and the pressure of gases in the furnace of vapor generators where a 15 fluid, as gas or oil, is employed and the invention has for its object the regulation of the supply of this fluid fuel to the furnace by and in accordance with changes in the rate of flow of vapor from the generator 20 or with changes in the static pressure of the vapor or with changes in both the dynamic and static pressures of vapors flowing from the generator, controlling the supply of air by and in accordance with the rate of supply 25 of fluid fuel and controlling the discharge of products of combustion by and in accordance with the pressure of gases in the furnace. The invention is hereinafter more fully described and claimed.
- 30 In the accompanying drawings forming a part of this specification, Figure 1 shows diagrammatically suitable means for controlling combustion where gas is employed as the fuel, Fig. 2 is a view showing a 35 modification in the fuel control and also a modification in the air control when oil is employed as fuel and Fig. 3 is a sectional elevation of a form of apparatus preferably employed when the supply of fuel is controlled by static pressure of vapor in the 40 boiler.

In the practice of the invention the pipe 1 through which gas is supplied to the furnace of the generator, is provided with a 45 valve 2 for regulating such supply. This valve is operatively connected to mechanism adapted to be operated by and in accordance with changes in the rate of flow of vapor from the generator or by and in 50 accordance with changes in the static pressure of the vapor or by and in accordance with changes in both the dynamic and static pressures of vapor flowing from the generator. It is preferred for this purpose to 55 employ mechanism shown and described in

application Serial No. 254975, filed September 20, 1918. This mechanism embodies a diaphragm indicated at 5 and subjected on its upper side to the total pressure of vapor flowing from the generator through the conduit C, the chamber above said diaphragm being so connected by a pipe 11 and Pitot tube or its equivalent to the conduit that the pressure exerted on the diaphragm will be equal to the static pressure in the generator plus or minus the pressure due to the rate of flow of vapor from the generator. A chamber intermediate the diaphragm 5 and a second diaphragm indicated at 6 is so connected to the generator or the conduit 60 C that the pressure maintained in said chamber will be equal to the static pressure of the vapor. The underside of the lower diaphragm 6 is subjected to a constant pressure which is substantially that of the normal or working pressure desired in the generator. The diaphragms 5 and 6 are so connected as described and shown in the above application, to a pilot valve controlling the flow of fluid under pressure to the cylinder 28 that for every change in the rate of flow 65 of the vapor or for every change in the static pressure of the vapor or change in both, the pilot valve will be opened proportionally to such change, thereby causing a 70 movement of the piston in said cylinder and the frame 29 carried thereby and connected by suitable means as the rope 4 to the valve 2 in the gas supply pipe 1. Suitable compensating mechanism operative by 75 the frame 29 is employed for closing the pilot valve after a predetermined movement of the frame. The frame is shifted its predetermined movement in one direction or the other, dependent upon whether 80 the changes in the dynamic or the static pressures or both in the conduit C are up or down, but in all cases an increase in the static pressure and a decrease in the rate of flow will effect through the described mechanism a closing movement of the regulating valve 2 proportional to such changes and increase in the rate of flow or decrease in static pressure will cause a reverse movement of the valve 2.

100 The air for the combustion of the gas is introduced into the furnace through the conduit 7, air being forced through the conduit by a blower 8 which is preferably operated at a constant speed. This uniformity 105

of feed of air is preferably attained by supplying the motor of the fan or blower with steam at a constant pressure below the normal or working pressure in the generator. 5 To this end steam is supplied to the pipe 9 which is connected to the motor of the blower through a reducing valve 10 of any suitable construction. The blower under such conditions will be so operated as to supply 10 at all times sufficient air for the maximum quantity of fuel to be fed to the furnace and the proportioning of air to be fed to the amount of fuel actually fed at any one time will be effected by a valve 11 arranged 15 in the air conduit and adapted to be controlled by and in accordance with the pressure of fuel in the supply pipe at a point intermediate the valve 2 and the furnace. The mechanism for operating the valve 11 consists 20 of a tank 12 containing liquid in which two inverted cups 13 and 14 are immersed; said cups being secured to a lever 15 on the opposite sides of the pivotal point of the lever. A nozzle 16 connected by a pipe 17 25 to the gas supply pipe 1 projects up into one of the cups as 13 to a point above the level of the liquid in the tank, so that the interior of the cup will be subjected to any changes in the pressure of gas in the pipe 1 between the control valve and furnace and 30 will rise or fall with such changes. The movement of the cup 13 will impart an opposite movement to the other cup 14, and as fully set forth in said application, this cup 35 will effect the displacement of the body of liquid inclosed therein, relative to the liquid exterior of the cup, and such displaced body of liquid will automatically counterbalance the pressure in the cup 13, thus insuring a movement of the cups and the lever proportional 40 to each incremental change in the pressure of gas in the pipe 1. The lever is connected by suitable means to a valve mechanism controlling the flow of fluid under pressure to the cylinder 18, having its piston connected by suitable means as a cord 19 to the valve 11 in the conduit 7. Suitable compensating mechanism operative by the piston is employed for closing the valve opened 45 by the lever, on a predetermined movement of the piston, as fully described and shown in the application Serial Number 254,975 above referred to, so that the valve 11 will be shifted to vary the supply of air proportionally to changes in the pressure of gas. 50

In order to insure effective combustion, the products of combustion should be discharged as soon as combustion occurs, but the rate of discharge should be so regulated 55 as to insure a maximum utilization of the heat generated. To these ends provision is made for regulating the escape or outflow of the products of combustion proportionally to the rate of combustion and to maintain a pressure of gases in the furnace not

greater than and preferably below atmospheric pressure. While a stack may be employed for drawing products of combustion from the furnace, it is preferred to employ an exhaust fan 20, operating at a rate which is constant but sufficiently high to withdraw gases when the generator is operated at its maximum rating. To attain these operating conditions, the motor of the fan is constructed to drive the fan at its maximum speed, with a steam pressure lower than the normal working pressure in the generator. In the construction shown, the motor of the exhaust fan 20 is connected to the pipe 9, which, as heretofore stated, is connected to the generator through a reducing valve 10. As the exhaust fan will operate to remove gases when the generator is working at its maximum rate, suitable means as a damper 21 are employed to regulate the discharge 85 of gases when the generator is operated at a lower rate and such damper is controlled by means operative by and in accordance with the pressure of gases in the furnace. While any suitable means may be employed 90 for this purpose, it is preferred to use, as shown at A, mechanism similar to that employed for controlling the valve 11 in the air conduit 7, the nozzle 16^a of such mechanism being connected to the furnace by a pipe 22 and the piston of the cylinder 18^a connected 95 to the valve or damper 21 by any suitable means as the cord 23.

In such cases a mechanism such as that shown in Fig. 3 is preferably employed, such 100 mechanism being described and claimed in application Serial Number 249654 filed August 14th, 1918, by Thomas A. Peebles. As shown in Fig. 3, the prime motor consists of a diaphragm 29 arranged in a shell or 105 casing 30 and preferably constructed as shown and described in Letters Patent No. 1094116 granted April 21st, 1914 to Francis H. Brown. The shell is so connected by a pipe 31 to the outlet pipe C of the boiler 110 that one side of the diaphragm will be subjected to the static pressure of the vapor in the generator. The opposite side of the diaphragm is subjected to a fluid pressure equal 115 to the normal working or static pressure of vapor in the outlet pipe. This pressure is applied through a fluid cushion formed in a chamber 32 communicating with the underside of the shell or casing 29 through a port 33. An inverted cup 35 is arranged in the 120 chamber which is then filled with liquid through a port 36 which is then closed by a suitable plug. In filling this chamber, air will be trapped in the cup thereby forming a resilient cushion. To establish the desired 125 pressure under the diaphragm, communication is established between the chambers on opposite sides of the diaphragm by opening the valve in said passage. After an equalization of pressure on opposite sides of the 130

diaphragm, the valve controlling the passage is closed so that thereafter one side of the diaphragm will be subjected to the pressure of the air cushion or the normal static pressure in the generator. The pressure on both sides being equal, any change in the static pressure in the generator will increase or decrease the pressure on the upper side of the diaphragm a proportional amount. The diaphragm 29 is connected by a rod 37 to the arm of a lever 38 which has its outer end adjustably connected to a pivotally mounted beam 39. A bell crank lever 40 is pivotally mounted in this beam and has an arm connected to the stem of the pilot valve 41 which may be of any suitable construction while the other arm of the bell crank lever is connected by a link 42 to a pivotally mounted standard 43. When the beam is shifted by the diaphragm, the bell crank lever will move with it and thereby shift the movable member of the pilot valve and admit pressure to one end of the cylinder 28 to move its piston which is connected to the frame 29. One of the legs of this frame has a block 45 secured thereto on which is adjustably mounted a bar 46 which is adapted to slide along a shoe pivotally mounted on the upper end of the pivotally mounted standard. This bar can be adjusted to any desired angle to the axis of the cylinder 28 so that by any desired movement of the frame the swinging standard may be moved sufficiently to so shift the bell crank lever as to close the pilot valve which has been opened by the movement of the beam operative by the diaphragm. It is characteristic of the construction employed that for each movement of the diaphragm an incremental movement will be imparted to the frame 29. On any variation of static pressure in the generator, the frame 29 will be shifted thereby shifting the valve 2 in the gas supply pipe.

When employing oil as a fuel, the mechanism employed for operating the air controlling valve 11 is adapted to be operated by and in accordance with changes in the rate of feed of oil to the furnace, a mechanism similar to that shown in Fig. 3 can be employed for controlling the valve 11 in the air supply duct as indicated in Fig. 2, by connecting the chamber above the diaphragm 6 to the oil supply pipe and establishing below the diaphragm a pressure substantially equal to the normal pressure in the oil supply pipe.

It is characteristic of the improvement described herein that the supply of fluid fuel is regulated by and in accordance with

the changes in the rate of flow of vapor from the generator or by and in accordance with changes in the static pressure of such vapor, or changes in both dynamic and static pressures of vapor flowing from the generator, the air for combustion is regulated by and in accordance with changes in the rate of supply of fuel to the furnace of the generator and the discharge of products of combustion is regulated by and in accordance with changes in the pressure of gases in the furnace.

I claim herein as my invention:

1. The method of regulating combustion in the furnace of a vapor generator utilizing a fluid fuel which consists in controlling the feed of the fuel by and in accordance with changes in the rate of flow of vapor from the generator and by and in accordance with the changes in the static pressure of the vapor in the generator and regulating the supply of air for combustion by and in accordance with changes in the quantity of fuel fed to the furnace.

2. The method of regulating combustion in the furnace of a vapor generator, utilizing a fluid fuel which consists in controlling the feed of the fuel by and in accordance with changes in the rate of flow of vapor from the generator and by and in accordance with changes in the static pressure of the vapor in the generator, regulating the supply of air for combustion by and in accordance with changes in the quantity of fuel fed to the furnace, and controlling the discharge of gases by and in accordance with changes in the pressure of gases in the furnace.

3. The method of regulating combustion in the furnace of a vapor generator, utilizing a fluid fuel which consists in controlling the feed of the fuel by and in accordance with changes in the static pressure of the vapor in the generator and regulating the supply of air for combustion by and in accordance with changes in the pressure of fuel fed to the furnace.

4. The method of regulating combustion in the furnace of a vapor generator utilizing fluid fuel which consists in regulating the supply of air for combustion by and in accordance with the changes in the pressure of fuel fed to the furnace and regulating the discharge of gases from the furnace by and in accordance with the pressure in the furnace.

In testimony whereof, I have hereunto set my hand.

JOHN M. HOPWOOD.
